UNITED STATES PATENT OFFICE

114,204

DESIGN FOR A DWELLING

Frank Lloyd Wright, Taliesin, Wis.

Application October 12, 1938, Serial No. 80,415

Term of patent 7 years

To all whom it may concern:

Be it known that I, Frank Lloyd Wright, a citizen of the United States and a resident of Taliesin, in the county of Iowa, post-office in Spring Green, State of Wisconsin, have invented a new, original, and ornamental Design for a Dwelling, of which the following is a specification, reference being had to the accompanying drawings, forming a part hereof.

In the drawings,

Figure 1 is a perspective view of a dwelling showing my new design all facades of the dwelling being the same.

I claim:

The ornamental design for a dwelling, as shown and described.

FRANK LLOYD WRIGHT.
